UNITED STATES PATENT OFFICE

2,584,353

RATCHETING JAW FOR PLIER-TYPE
WRENCHES

John Keiser, Windsor, Colo.

Application June 17, 1949, Serial No. 99,740

2 Claims. (Cl. 81—180)

1

This invention relates to a plier-type wrench, and has for its principal object the provision of highly efficient means which will enable the wrench to ratchet upon cylindrical surfaces, such as pipe and pipe fittings.

Another object is to provide a simple ratcheting device which will automatically grip the pipe, and which will operate without exerting a crushing action on the pipe.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a side view of a typical plier-type wrench, with the invention applied thereto, illustrating the ratcheting device in the gripping or turning position;

Fig. 2 is a similar view of the jaw portion of the wrench of Fig. 1, illustrating the ratcheting device in the ratcheting or returning position;

Fig. 3 is a vertical cross-section through the jaws of the wrench, taken on the line 3—3, Fig. 2;

Fig. 4 is a longitudinal section through the wrench jaws, taken on the line 4—4, Fig. 3; and

Fig. 5 is a detail, perspective view of the improved ratcheting device employed in the improved wrench jaws.

In the drawing, typical parts of a plier-type wrench are illustrated and designated by numerals as follows: Upper handle 10, lower handle 11, toggle arm 12, fulcrum screw 13, and returning spring 14.

The improved jaws for the illustrated type of wrench comprise a solid upper jaw 15 extending forwardly and downwardly from the forward extremity of the upper handle 10, and a lower solid jaw 16 formed on a swinging jaw plate 17. The plate 17 is hingedly mounted on a hinge pin 18 within the upper handle 10, and is connected by means of a second hinge pin 19 to the forward extremity of the lower handle 11. The spring 14 extends from a spring ear 20 on the plate 17 upwardly and rearwardly to a connection 21 within the upper handle 10.

It can be seen that if the lower handle 11 be forced toward the upper handle 10, the fulcrum pin 22 will cause the toggle arm 12 to pry against the extremity of the fulcrum screw 13 so as to

2

swing the plate 17 forwardly to cause the lower jaw 16 to approach the upper jaw 15. The degree of separation of the jaws can be adjusted by changing the position of the fulcrum screw 13.

The improved ratcheting device comprises an arcuate ratcheting foot 23 provided with an upstanding, semi-cylindrical hinge ear 24 having an opening 25 formed therethrough for receiving a hinge pin 26. The lower arcuate surface of the foot 23 is provided with transversally extending ratchet teeth 27.

The arcuate surface upon which the teeth 27 are formed is eccentric to the axis of the opening 25; that is, this surface is closer to the axis 15 of the opening 25 at the heel of the foot 23 than at the toe thereof. The foot portion 23 is slightly wider than the upper jaw 15, and the ear 25 is narrower than this jaw.

The upper jaw is formed with an internal, semi-cylindrical notch 28 for receiving the rounded, semi-cylindrical upper extremity of the ear 24 so as to form a bearing for the latter. The two sides of the upper jaw extend downwardly at each side of the notch 28 to form arcuate bearing edges 29 which bear against the sides of the upper surface of the foot 23. The pin 26 simply holds the ear 24 in its notch. It does not act as a bearing for the ear, since the bearing is formed by the arcuate surface of the ear bearing in the arcuate notch 28, and by the sides of the foot 23 bearing against the arcuate bearing edges 29.

A U-shaped spring 30 acts between a shoulder 31 in the upper jaw and the upper surface of the toe portion of the foot 23 to constantly urge the ratchet member toward the position of Fig. 4. A substantially 90° V-shaped, article-receiving notch 32 is formed in the lower jaw 16 below the ratcheting foot 27.

The wrench can be slipped over a cylindrical article, such as indicated at 33, by simply forcing the jaws over the article so that the latter will swing the ratcheting foot rearwardly, as shown in Fig. 2. If the handles be now swung in the direction of the arrow "A" in Fig. 1, the eccentric surface of the ratcheting foot 23 will roll against the article 33, constantly increasing the pressure thereagainst due to the eccentricity of the surface, until sufficient grip has been obtained from the teeth 27 to rotate the article 33.

If the handles be now swung in the direction of the arrow "B" of Fig. 2, the ratcheting foot will swing rearwardly, releasing the article, as shown in Fig. 2, and allowing it to rotate against

the smooth surfaces of the V-shaped notch 32 to a new gripping position.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. The combination with a plier-type wrench of the type having an upper and a lower jaw, of means for ratcheting a cylindrical article between said jaws, comprising: a ratcheting foot; a rounded hinge ear arising from said foot and resting in a similarly rounded receiving socket in the upper jaw; a hinge pin passing through said upper jaw and through said hinge ear; a lower arcuate surface on said foot, said arcuate surface being eccentric of the axis of said hinge pin; and a V-shaped, article-receiving notch formed in the lower jaw below said ratcheting foot.

2. The combination with a plier-type wrench of the type having an upper and a lower jaw, of means for ratcheting a cylindrical article between said jaws, comprising: an eccentric toothed ratcheting foot; a rounded hinge ear arising from said foot and resting in a similarly rounded receiving socket in the upper jaw; a hinge pin passing through said upper jaw and through said

hinge ear; a lower arcuate surface on said foot, said arcuate surface being eccentric of the axis of said hinge pin; a V-shaped, article-receiving notch formed in the lower jaw and positioned opposite said ratcheting foot, said ear being relatively narrower than said foot so that the latter will project outwardly at each side of said ear; and rounded protuberances formed on the side edges of said upper jaw in contact with the outwardly projecting sides on said foot and acting as a bearing to receive the thrust of said ratcheting foot.

JOHN KEISER.
